(**) Term: **14 Years**

CLAIM

(21) Appl. No.: **29/297,240**

The ornamental design for the autorefractokeratometer with integrated pachymeter, as shown and described.

(22) Filed: **Nov. 7, 2007**

DESCRIPTION

(51) LOC (9) Cl. **24-01**
(52) U.S. Cl. **D24/172; D10/46**
(58) **Field of Classification Search** D10/46;
D24/172; 351/200, 204, 205; 356/128, 129,
356/130-137

See application file for complete search history.

FIG. 1 is a perspective view of the autorefractokeratometer with integrated pachymeter, incorporating the new design; and

FIG. 2 is a front elevational view thereof;

FIG. 3 is a rear elevational view thereof;

FIG. 4 is a right side elevational view thereof; and

FIG. 5 is a left side elevational view thereof;

FIG. 6 is a top view of the autorefractokeratometer with integrated pachymeter; and,

FIG. 7 is a bottom view of the autorefractokeratometer with integrated pachymeter.
